SUPPORTS FOR DRAPERY, CURTAINS, WINDOW SHADES AND THE LIKE

Florabelle R. Newcomb, 904 N. 7th St.,
Camden, N.J.

Filed Jan. 6, 1958, Ser. No. 707,376

2 Claims. (Cl. 248—261)

This invention relates to supports for draperies, curtains, window shades, and the like, and it relates more particularly to a novel device by means of which the various kinds of brackets used for mounting draperies, curtains, window shades or the like, may be easily and conveniently arranged for a particular installation, and subsequently rearranged and adjusted, as may be desired from time to time.

Heretofore, whenever draperies, curtains, window shades and the like were to be hung, it was necessary to secure the various special brackets employed for such purpose, at the desired locations, by means of wood screws or nails which defaced the wooden trim, and in some instances the walls. Such damage would, in the course of time, be quite considerable, particularly if any rearrangement or adjustment of the hanging was required by reason of frequent changes in decorative styles, or for any other purpose.

Furthermore, the proper mounting of the aforesaid brackets on the wooden window and door trim, as well as on plaster walls, requires a certain amount of skill, and most of the work must be done by an operator on a stepladder, which involves danger of falling, particularly when the same is attempted by persons having relatively little skill and agility.

The principal object of the present invention is to provide a simple and inexpensive device by means of which the brackets commonly used for mounting draperies, curtains, window shades, and the like, may be properly positioned, shifted, and adjusted by persons of little skill and ability.

A further object of the invention is to provide a device of the character aforesaid, by means of which most of the work in the locating and securing of the brackets employed for a particular installation may be done at a convenient place without danger of falling or injury to the person hanging the draperies, curtains, or window shades.

A further object of the invention is to provide a device of the character aforesaid, the use of which will minimize defacement of and damage to the wooden window and door trim, as well as the walls, to which the brackets or fixtures are usually directly attached.

The nature and characteristic features of the invention will be more readily understood from the following description, taken in connection with the accompanying drawings forming part hereof, in which:

Figure 1 is a top or plan view, certain parts being broken away, of a supporting device embodying the main features of the present invention, the same being shown with various brackets and curtain rods attached thereto.

Fig. 2 is a front elevation of one end portion of said device with the brackets and curtain rods removed;

Fig. 3 is a vertical sectional view, taken on the line 3—3 of Fig. 1;

Fig. 4 is a vertical sectional view, enlarged, taken on the line 4—4 of Fig. 1;

2

Fig. 5 is a vertical sectional view, enlarged, taken on the line 5—5 of Fig. 1;

Fig. 6 is a vertical sectional view, enlarged, but with a conventional curtain rod bracket secured to the carriage; and

Fig. 7 is a view similar to Fig. 6, but with a window shade bracket secured to the carriage.

It should, of course, be understood that the description and drawing herein are illustrative merely, and that various modifications and changes can be made in the structure disclosed without departing from the spirit of the invention.

Referring to the drawing, in the particular embodiment of the invention therein shown, the device consists essentially of a rail or track 10, fixedly and permanently secured to the wooden trim of a door or window, or to the wall of a room, wherever it is desired to have draperies, curtains, window shades or the like, and a carriage 11 at each end comprising a bracket or fixture carrying plate 15 adjustably mounted on the rail 10, the arrangement being such that the desired brackets and supports for the curtain rods or other parts may be mounted on and secured to the carrying plate 11 at any convenient location prior to the attachment thereof to the rail or track 10.

The rail 10 comprises a strip or rod of metal, which may be of rectangular cross-section, although other shapes may be used for the rail 10 if desired, providing the top and bottom surfaces of said rail are non-flaring, for a reason to be hereinafter set forth. The rail 10 may be of any required length, and in the commercial development of the invention the rails will be supplied in various lengths whereby the user may select a length or lengths suitable for a particular use and thus obviate the necessity of cutting the same.

The rail 10 is provided with countersunk holes 12 through which wood screws 13 may be passed to be threaded in the moulding or wooden trim of the window or door frame, or in the wall, whereby the rail 10 may be permanently secured at the desired location.

The carriages 11 are slidably mounted on the track 10. Said carriages 11 may each comprise a flat plate member having ribs 15 on the rear face thereof, said ribs 15 being shaped and spaced complementary to the rail 10 so that said carriages 11 may be placed from the front on the rail 10 and thereafter shifted and secured at desired locations on the rail 10. The carriage 11 may be provided with a longitudinal slot 16 between the ribs 15, and a fastening screw or bolt 17 may be passed through the slot 16 and threaded in a hole 18 in the rail 10, thereby to secure the carriage at various adjusted longitudinal locations.

The plate member comprising each carriage 11 is provided at the ends thereof with a series of pairs of vertically aligned slots 19 by means of which brackets, of any of the desired forms which are available for hanging draperies, curtains, etc., may be secured on the carriage at the preferred and selected locations.

For example, as shown in Figs. 1 and 3 of the drawing, a bracket 20 of a well known available type, commonly used for supporting telescoping curtain rods 22, may be secured, at the far end of each carriage, by means of small bolts 21 passing through the proper slots 19 in the carriage.

On the other hand, in Fig. 6 of the drawing there is shown, secured to the carriage, another and different type of curtain rod bracket 23, while in Fig. 7 of the drawing a type of bracket 24 is shown such as is used for supporting a window shade of the roller type. In each of the arrangements shown in Figs. 6 and 7 the brackets are secured to the carriage by means of bolts 21.

It will be noted that, in the use of the device as above

described, the carriages 11 may be detached from the rail 10 by the removal of the securing bolts 17, whereupon the brackets employed in connection with a particular arrangement may be conveniently mounted on and secured to the carriages 11 at the desired locations thereon, after which the carriages 11 may be replaced as assembled units on the rails 10, at the desired adjusted longitudinal positions, and secured in place by the replacement and tightening of the securing bolts 17.

It will be apparent that in the use of the device of the present invention most of the work may be conveniently done at safe places, and that in the event of sidewise adjustment of either or both of the carriages being required, this may be easily and readily accomplished.

I claim:

1. A support for draperies, curtains, window shades and the like, comprising a rail to be permanently secured in a horizontal position to a portion of a building structure, said rail being substantially rectangular in cross-section, a carriage at each end of the rail comprising a flat plate member having longitudinal ribs on its rear face spaced and shaped complementary to the rail, said carriages each having a longitudinal slot disposed between the aforesaid ribs, fastening bolts extending through said slots and mounted in the rail to secure said carriages in adjusted longitudinal locations on said rail, and said carriages each having a plurality of slots extending therethrough for mounting conventional drapery, curtain, window shade, and similar brackets on said carriage at desired selective locations, the arrangement being such that

25
30

the carriages, with the desired brackets mounted, and secured thereon, may be frontally placed and may be secured at the desired longitudinal locations on the rail.

2. A support for draperies, curtains, window shades and the like, comprising a rail to be permanently secured in a horizontal position to a portion of a building structure, said rail being substantially rectangular in cross-section, a carriage at each end of the rail comprising a flat plate member having longitudinal ribs on its rear face spaced and shaped complementary to the rail, said carriages each having a longitudinal slot disposed between the aforesaid ribs, fastening bolts extending through said slots and threaded in the rail to secure said carriages in adjusted longitudinal locations on said rail, and said carriages each having a plurality of pairs of vertically aligned slots extending therethrough for mounting conventional drapery, curtain, window shade and similar brackets on said carriage at desired selective locations, the arrangement being such that the carriages, with the desired brackets mounted and secured thereon, may be frontally placed and secured at the desired longitudinal location on the rail.
